MASSAGE TABLE

Kathleen Tammen, Tucson, Ariz.

Application June 13, 1947, Serial No. 754,316

6 Claims. (Cl. 128—52)

1

This invention relates to health devices and more particularly to a table for exercising and massaging various parts of the body.

Numerous types of devices have been employed for giving proper treatment to various parts of the human body, however, they have not been found completely satisfactory or practical for many reasons.

It is an object of the invention to provide apparatus for treating the ankles, legs, thighs, hips, back, shoulders, and neck of an individual.

Further objects and advantages of the invention will be apparent from the following description taken in conjunction with the accompanying drawings, wherein:

Fig. 1 is a side elevational view of a massage table illustrating one embodiment of the present invention;

Fig. 2, a top plan view of the massage table illustrated in Fig. 1, on a somewhat reduced scale;

Fig. 3, a front perspective view thereof, on a still further reduced scale;

Fig. 4, a side elevational view, on an enlarged scale, of the mechanism for producing movement of a cushion intended to support the shoulder and back of the user, with the parts in neutral or inoperative position;

Fig. 5, a side elevational view, similar to Fig. 4, but illustrating the parts in an operative position;

Fig. 6, a perspective view, also on an enlarged scale, of the motion producing yoke;

Fig. 7, a fragmentary perspective view, on a still further enlarged scale, of one of the control blocks, parts being broken away to illustrate the locking means for securing the block in adjusted position; and

Fig. 8, a front elevational view of the massage table, on a scale similar to that of Fig. 1.

With continued reference to the drawings, the invention comprises a massage table mounted upon a horizontally disposed lower frame 10 formed from angle iron members and substantially rectangular in shape. Preferably this frame is supported upon legs 11 and rollers 12 are also provided, raisable and lowerable for supporting the device which may thus readily be moved about, from place to place. This lower frame is further provided with upright members 13, horizontally disposed upper longitudinal members 14 and intermediate longitudinal members 15 extending from the front end of the device to a pair of intermediate upright members.

A motor 16 is mounted upon the frame 10 and

15 this motor, through a belt drive or the like 17, transmits power to a pulley 18 secured upon a transversely disposed shaft 19 journaled in suitable bearings supported within the framework of the device. A second pulley, not shown, is secured to the shaft 19 and, through a belt 20 and pulley 21, power is transmitted to a second transversely journaled shaft 22. An eccentric 23 is mounted upon the shaft 22 and by means of a connecting rod 24 oscillatory motion is imparted to a yoke member 27 pivotally mounted as indicated at 28 between vertically disposed brackets which are mounted at each side of the frame between the upper and intermediate longitudinal members 14 and 15, as illustrated more particularly in Fig. 6 of the drawings. Preferably the yoke 27 is provided with a vertically disposed brace 32 positioned intermediate the extremities thereof and a yoke arm 26 is fixedly secured to the brace 32 by any suitable means such as welding, or the like, the upper extremity of the connecting rod 24 being pivotally connected to the yoke arm adjacent the free extremity thereof, as indicated at 25.

25 The yoke 27 comprises a substantially rectangular frame and includes upper and lower members 29 and 30, respectively, between which the brace 32 is mounted. The yoke 27 is further provided with a plurality of guide rods 31 disposed vertically in spaced relation adjacent each end thereof. In the embodiment of the invention disclosed, four (4) of such guide rods have been illustrated, two of them being located on each side of the brace 32 which is preferably positioned substantially centrally of the length of the yoke 27.

30 Each of the guide rods 31 is provided with a plurality of axially aligned spaced depressions or 40 sockets 33 for the selective reception of a ball 34 which is normally urged into a socket by means of a coil spring 35, or the like, a screw-threaded plug 36 having a wrench socket 37 being provided whereby the spring pressure exerted upon the 45 ball may be adjusted. This spring-pressed ball serves to secure an adjustable control block 40 in position upon a guide rod 31, for a purpose to be described more fully hereinafter, it being understood that the control blocks are vertically adjustable upon the guide rods and that a separate control block is provided for each rod.

To provide adequate lubrication for control blocks, guide rods and spring-pressed balls, there is provided an oil channel 38 having a fitting 39 in the extremity thereof, whereby oil may be sup-

55

plied to the guide rods and permit free adjustment of the control blocks thereupon.

Each control block is provided with opposed fittings 40 intended for the reception of pivot pins 41 whereby a control bridle comprising opposed side members 42 may be pivotally mounted upon the block 40'. Between the opposed extremities of the pair of side members 42 which comprises each bridle are cross members 43 and 44 connected, respectively, to block connecting rods and control levers 45 and 46. The extremity of each connecting rod 45 is yieldably secured to a substantially vertically depending arm 47, preferably reinforced by an angularly disposed bracket 48. Cushion members 49 are mounted upon the rod 45, one on each side of the arm 47, and are confined against the faces of the arm by means of suitable nuts 50 threadedly engaged with the complementarily threaded extremity of said rod. Each connecting rod 45 extends through a suitable aperture (not shown) in the arm 47 to which the rod is attached and thus the angular relationship between connecting rod and arm may be varied in accordance with the position of the control block without any necessity for a universal joint or similar connection. Oscillation of the yoke 27 by the connecting rod 24 and eccentric 23 takes place about a horizontal axis transverse to the device and imparts a similar oscillatory motion to the control blocks 40' each of which, through the oscillation thereof, imparts a reciprocating motion to the connecting rod 45 associated therewith.

As is particularly illustrated in Fig. 4 of the drawings, the central or neutral position of each control block is in horizontal alignment with the pivotal mounting 28 of the yoke 27, the pivotal points 41 of the control blocks being disclosed as in transverse alignment with the pivotal mounting 28. Thus, when in this position, oscillation of yoke and control blocks will impart no motion to the connecting rods 45. When a control block is moved to the uppermost position disclosed in Fig. 5 of the drawings, oscillation of the yoke will result in reciprocation of the control block connecting rod to the positions illustrated in dotted lines. Where the control block is moved to the intermediate position between that shown in Fig. 5 and the neutral position of Fig. 4, a lesser degree of reciprocatory motion would be imparted to the control block connecting rod. Since upper and lower positions are provided for each control block, that is, both above and below the neutral position, it will be obvious that any control block adjusted to a position below neutral will impart an opposite reciprocatory motion to its associated connecting rod with respect to the motion imparted by control blocks adjusted to a position above neutral.

A knob 51 may be provided on the extremity of each control lever 46 to permit ready adjustment of each control block 40' on its associated guide rod 31, it being understood that, as previously stated, the degree of elevation or depression of such knobs will control the degree of motion or length of stroke imparted to the control block connecting rods 45 as well as the related direction of movement thereof.

The massage table per se comprises a plurality of pairs of pads or cushions 52, 53 and 54 for supporting, respectively, the back and shoulders, the hips, and the legs. Each cushion of these pairs of cushions is supported upon an appropriate frame, formed from suitable material such as angle iron, or the like. The cushions 52, which

are intended to support the back and shoulders are supported upon frames 55 which are pivotally mounted within the lower frame 10 by means of links 58 having pivotal connection to the opposed 5 intermediate longitudinal members 15. Similarly, the cushions 53 which are intended to support the hips and are on a higher horizontal level than the cushions 52, are supported upon frames 56 which are pivotally mounted within the lower 10 frame 10 by means of links 59 having pivotal connection with ears 60 or the like formed integrally with or otherwise rigidly secured to opposed pairs of upright members 13. Each of the frames 55 and 56, there being four such frames disclosed, 15 has an arm 47 and bracket 48 fixedly secured therebeneath and an associated control block connecting arm 45 is attached to each arm 47, as has been previously described in detail, adjacent the lower extremity thereof. Thus, oscillation of 20 a control block will impart reciprocatory motion to one of these frames and the cushion supported thereon dependent upon the adjustment of the control levers 46. One such adjustment, as well as the relationship between control levers and 25 cushions, has been particularly illustrated in Fig. 8 of the drawings where the cushion supporting the left shoulder and the cushion supporting the right shoulder are adjusted for movement at maximum stroke in opposite directions while the 30 cushion supporting the left hip is adjusted for movement at a maximum stroke in coordination with the right shoulder and the cushion supporting the right hip is adjusted for movement at a maximum stroke in coordination with the left shoulder.

No such reciprocatory movement is required or provided for the pair of cushions 54 intended to support the legs. Each of these cushions is supported upon a suitable frame 57, preferably 40 formed from angle iron or the like, pivotally supported upon arcuate brackets 61 attached to the lower frame 10 on the end thereof remote from the control block mechanism. Preferably the frames 57 are provided with opposed braces 62, 45 the lower extremities of these braces being adjustable within a notched rack or the like 63 to permit change in angularity of the leg cushions or the dropping thereof, out of the way when not in use.

Exercise means for the legs is provided, a preferred form thereof comprising an upright tubular member 64 mounted between the cushions 54 and provided with a cap portion 65 within which is journaled suitable crank arms 66 having foot-engaging pedal portions 67. The intermediate portion of the crank arms, which passes through the cap portion 65, is encircled by a suitable strap or the like (not shown) and means, such as a hand-wheel 68, is provided whereby the tension exerted by this strap may be varied. The lower extremity of the tubular member 64 is pivotally supported, as by a pin and slot or other suitable connection, upon an arm 69 having pivotal connection with a bracket 70 depending beneath the frame 57. Thus, the distance between the pedals 67 and the cushions 53 may be readily varied, in strict accordance with the length of the legs of the person using the device or for moving the tubular member downwardly, when the use thereof is not desired.

Preferably an automatic timing device 71 is provided to permit the operation of the device for a predetermined period of time, as is well known in this and related arts.

The operation of the device is particularly

simple. The individual undergoing treatment reclines upon the table with the back and shoulders supported upon the cushions 52 and the hips supported upon the cushions 53, the calves of the legs being supported upon the cushions 54, these latter cushions being pivotally adjustable about the upper extremities of the arcuate brackets 61 and not associated with or controlled by the mechanism of the table. The pairs of cushions 52 and 53 may be designated for purposes of convenience as left and right-hand cushions, there being four cushions in all with individual associated control mechanism for each cushion, which thus becomes a body-treating member.

Reciprocatory motion may, if desired, be imparted to all four cushions simultaneously or motion may be selectively imparted to one or more of the cushions as the nature of the desired treatment may require. For example, the back and shoulders may be permitted to remain at rest upon the cushions 52 while motion is imparted through the cushions 53 to the hips or thighs only, resulting in pelvic or localized body treatment of a specific character. When necessary, such massage or treatment may be imparted to one hip or thigh only, the other cushion being adjusted through its associated control mechanism so as to remain at rest.

In like manner, treatment may be administered to one shoulder and side of the back, or to both shoulders, as may be necessary, the movement of each body member being selectively controllable. It will be obvious that the greater the distance the adjusting or control blocks 40' are moved from neutral, the greater the degree of movement which will be imparted to the associated body-treating member. Similarly, with the control block 40' in position immediately adjacent neutral, a very gentle degree of motion will be imparted to the body-treating member.

Since each control lever has an adjustment on either side of a central neutral position, the cushions of a pair of body-treating members may be caused to move either in opposition or in unison with respect to each other. For appropriate pelvic treatment, movement in opposition is desirable. For a simple hip massage, the patient reclines upon his side substantially centrally of the pairs of cushions, periodically reversing positions, and the cushions 53 are reciprocated in unison. Where necessary, suitable weights, such as sand bags or the like, may be placed over the abdominal area or hips.

The leg-exercising device, or pedal pusher, requires active participation by the patient who may recline upon the cushions 52 and 53 and push the pedals with the feet.

From the foregoing, it will be readily apparent that the present invention includes a machine of unitary construction which may be readily moved about from place to place and which is provided with body-treating cushions or members for selectively, variably, and independently treating the left and right shoulder portions of the back, the hips, and the legs, in accordance with requirements and as may be desired.

It will be obvious to those skilled in the art that various changes may be made in the invention without departing from the spirit and scope thereof and therefore the invention is not limited by that which is shown in the drawings and described in the specification but only as indicated in the appended claims.

What is claimed is:

1. In a mechanical massage table, a frame, two

pairs of body-treating members comprising two shoulder- and back-treating members and two hip-treating members movably mounted on said frame, a motor on said frame, an oscillatable yoke on said frame, an eccentrically driven connection between said motor and said yoke, a plurality of guide rods on said yoke, a control block slidably adjustable on each guide rod from a position above to a position below the axis of oscillation of said yoke, a bridle pivotally connected to each control block, a connecting rod secured at one extremity to each bridle, the opposite extremity of each connecting rod being yieldably secured to an associated body-treating member, and a control lever on each bridle for independently varying the adjustment of each control block to selectively control the degree of movement imparted to the associated body-treating member whereby each member of a pair of body-treating members may selectively move in unison or in opposition to the other member of said pair.

2. In a mechanical massage table, a frame, two pairs of body-treating members movably mounted on said frame, said body-treating members comprising two shoulder- and back-treating members and two hip-treating members, a motor on said frame, an oscillatable yoke on said frame, an eccentrically driven connection between said motor and said yoke to produce oscillation thereof, a plurality of guide rods on said yoke, a control block slidably adjustable on each guide rod from a position above to a position below the axis of oscillation of said yoke, a bridle pivotally connected to each control block, a connecting rod secured at one extremity to each bridle and having its opposite extremity yieldably secured to an associated body-treating member, and means for independently varying the adjustment of each control block to selectively control the degree of movement imparted to the associated body-treating member whereby each member of a pair of body-treating members may selectively move in unison or in opposition to the other member of said pair.

3. In a mechanical massage table, a frame, two pairs of body-treating members movably mounted on said frame, said body-treating members including two shoulder- and back-treating members and two hip-treating members, a motor on said frame, an oscillatable yoke on said frame, an eccentrically driven connection between said motor and said yoke to produce oscillation thereof, a plurality of guide rods on said yoke, a control block slidably adjustable on each guide rod from a position above to a position below the axis of oscillation of said yoke, a connecting rod having one extremity pivotally connected to each control block and having its opposite extremity yieldably connected to an associated body-treating member, and means for independently varying the adjustment of each control block to selectively control the degree of movement imparted to the associated body-treating member whereby each member of a pair of body-treating members may selectively move in unison or in opposition to the other member of said pair.

4. In a mechanical massage table, a frame, body-treating members movably mounted on said frame, said body-treating members including two shoulder- and back-treating members and two hip-treating members, an oscillatable yoke on said frame, means for oscillating said yoke, a plurality of guide rods on said yoke, a control block slidably adjustable on each guide rod from

a position above to a position below the axis of oscillation of said yoke, a connecting rod having one extremity pivotally connected to each control block and having its opposite extremity yieldably connected to an associated body-treating member, and means for independently varying the adjustment of each control block to selectively control the degree and direction of movement imparted to the associated body-treating member.

5. In a mechanical massage table, a frame, body-treating members movably mounted on said frame, said body-treating members comprising two shoulder- and back-treating members and two hip-treating members, an oscillatable yoke on said frame, means for oscillating said yoke, a plurality of guide rods on said yoke, a control block slidably adjustable on each guide rod from a position above to a position below the axis of oscillation of said yoke, a connecting rod having one extremity secured to each control block and having its opposite extremity secured to an associated body-treating member for imparting movement thereto, and means for independently varying the adjustment of each control block to selectively control the degree and

direction of movement imparted to the associated body-treating member.

6. In a mechanical massage table, a frame, two pairs of body-treating members movably mounted on said frame, said body-treating members comprising two shoulder- and back-treating members and two hip-treating members, means for selectively imparting movement to each of said body-treating members, and means for independently varying the degree and direction of movement of each body-treating member whereby each member of a pair of body-treating members may selectively move in unison or in opposition to the other member of said pair.

15 KATHLEEN TAMMEN.
